UNITED STATES PATENT OFFICE.

ALBERT H. TAYLOR, OF EASTON, PENNSYLVANIA, ASSIGNOR TO INGERSOLL-RAND COMPANY, OF NEW YORK, N. Y., A CORPORATION OF NEW JERSEY.

HAMMER-DRILL.

968,891.

Specification of Letters Patent. Patented Aug. 30, 1910.

Application filed October 1, 1907. Serial No. 395,338.

To all whom it may concern:

Be it known that I, ALBERT H. TAYLOR, a citizen of the United States, and resident of Easton, in the county of Northampton and 5 State of Pennsylvania, have invented a new and useful Improvement in Hammer-Drills, of which the following is a specification.

My invention consists in certain improvements in that class of pneumatic tools known 10 as hammer drills in which an air power feed is provided for forcing the tool forward and holding it in its working position.

The object of my invention is to provide a controlling valve in the head block of the 15 drill, which valve is so constructed and arranged that it may be operated to control the admission of air to the air feed and to the hammer at pleasure thus rendering the machine easy to handle and to set up.

20 A further object is to provide a tool in which the controlling valve is held onto its seat by air pressure whereby the wear is taken up automatically.

My invention further consists in means 25 for automatically locking the controlling valve in its various positions so as to prevent the same from being moved out of its desired position by the jars incident to the operation of the tool.

30 Practical embodiments of my invention are represented in the accompanying drawings, in which—

Figure 1 represents a portion of an air feed hammer drill, partially in side elevation and partially in longitudinal central section, with my improvements applied thereto, the controlling valve being in position to close communication from the air supply both to the air feed and to the hammer, the air feed being in open communication with atmosphere, Figs. 2 and 3 are detail sections showing the location of the several ports when the valve is in the position shown in Fig. 1, Fig. 4 is a detail view partially in section and partially in side elevation, the controlling valve being shown in position to open the air supply to the air feed and close communication between the air supply and the hammer, the communication between the air feed and atmosphere also being shut off, Figs. 5 and 6 are detail sections showing the location of the several ports when the valve is in the position shown in Fig. 4, Fig. 7 is a view similar to Fig. 4 55 with the controlling valve in position to open

communication between the air supply and both the air feed and hammer, communication between the air feed and the atmosphere being closed, Figs. 8 and 9 are detail sections showing the location of the ports when the valve is in the position shown in Fig. 7, Fig. 10 is a detail top plan view of the locking plate, and Fig. 11 is a view of a portion of a hammer drill of slightly modified form in which the piston rod is attached to the head 60 block instead of the air feed cylinder as shown in Fig. 1.

The hammer cylinder is denoted by 1, and its head block by 2.

In the preferred form, the air feed cylinder 3 is attached directly to the head block 2 while in the form shown in Fig. 11, the piston rod 4 is attached to the said head block.

In the form shown in Fig. 1, the head 5 of 75 the piston rod 4 is fitted to slide in the air feed cylinder 3 and the rod 5 extends rearwardly through the outer end 6 of said cylinder to form the rear support for the tool. Air ducts 7 lead from the space back of the 80 piston head 5 to atmosphere.

The head block 2 of the tool is provided with a hole therethrough, a portion of which forms a taper seat 8 for the tapered portion 9 of a controlling valve. The cylindrical portion 10 of said valve at the end of its tapered portion is provided with an angular portion 11 on which is fixed the locking plate 12 and the handle 13 of the valve exterior to the head block. This locking plate 90 85 95 12 has its inner face adjacent to the outer face of the head block and is provided with three shallow recesses 14, 15 and 16, arranged to respectively receive and retain against unintentional removal the rounded end of a spring actuated sliding pin 17 mounted in the head block. The locking plate 12 is further provided with shoulders 18, 19, arranged to engage the projecting end of a stop 20 on the head block for limiting the rotary movement of the controlling valve in both directions.

An air supply pipe 21 is secured to the head block 2 by a collar 22 having a screw threaded engagement with the hole in the 105 head block beyond its taper seat 8. The controlling valve is provided with a chamber 23 in open communication with the air supply pipe 21.

Ports 24 and 25 lead from the chamber 23 110

to the seat 8 in the head block. Ports 26 and 27 lead respectively from the seat 8 to the air feed space 28 and to the hammer feed space 29, said ports being in the same plane as the valve ports 24 and 25. The valve is further provided with a through port 30. Ports 31 and 32 in the same plane as the through port 30 lead from the valve seat 8 respectively to the air feed space 28 and to the external atmosphere.

In the form shown in Fig. 11, the construction of the controlling valve and the head block is the same as in the form shown in Fig. 1. Instead of the air feed cylinder 3 being secured directly to the head block, the piston rod 4 is secured directly to the head block and it extends rearwardly through the inner end 33 of the cylinder 3, the outer end of said cylinder being provided with a rearward extension 34 for forming the rear support for the tool. In this form the space in front of the piston head 5 is at all times open through atmosphere through the ports 35 in the end 33 and the piston rod 4 is made hollow for opening communication to the space at the other end of the said piston head.

In operation, supposing the parts to be in the position shown in Figs. 1, 2 and 3, the air supply will be shut off from the air feed and from the hammer. The air feed will be open to external atmosphere through the ports 31, 30, 32, when the valve is in this position. Also the shoulder 19 of the locking plate on the valve will be in engagement with the stop 20 and the locking pin 17 will be located within its socket 14. The movement of the valve into the position shown in Figs. 4, 5 and 6, will close communication from the air feed to external atmosphere and will open communication from the air feed to the air supply but will not open the air supply to the hammer. When the parts are in this position, the tool will be automatically fed up to its work and held by the air feed. The valve will be held against unintentional movement by the engagement of the spring actuated pin 17 with its socket 15. The next movement of the valve into the position shown in Figs. 7, 8 and 9, will bring the air supply into open communication with the hammer and still keep the communication open between the air supply and the air feed thus starting the operation of the tool. The valve is stopped in this position by the engagement of the shoulder 18 on the locking plate with the stop 20 and is held in such position against unintentional removal by the engagement of the spring actuated pin 17 with its socket 16.

By returning the controlling valve to its original position shown in Figs. 1, 2 and 3, the air supply is cut off from both the hammer and the air feed and the air feed is

brought into open communication with the external atmosphere thus removing the pressure from the air feed piston and permitting the readjustment of the tool to any other desired position.

In the construction above set forth, it will be seen that a very simple and effective means is employed for controlling the admission of air supply to the air feed and the hammer. It will furthermore be seen that all wear between the valve and its seat is taken up automatically by the constant air pressure from the air supply. Furthermore, means are provided for locking the valve in its several positions against unintentional removal. Also, in the form shown in Fig. 1, a very rigid structure is obtained by the direct attachment of the air feed cylinder to the head block instead of the attachment of the air feed piston to the head block.

While the invention has been described in connection with an air power feed hammer drill any other fluid power may be utilized and any type of tool may be employed without departing from the spirit and scope of my invention.

What I claim is:

1. In an air feed hammer drill, a head block, an air supply, an air feed cylinder, its piston and a manually operated valve in the head block having passages arranged when in one position to open communication between the air supply and the air feed cylinder and close communication between the air supply and hammer and when in another position to open communication between the air supply, the air feed cylinder and the hammer.

2. In an air feed hammer drill, a head block, an air supply, an air feed cylinder, its piston and a manually operated valve in the head block having passages arranged when in its first position to open communication between the air feed cylinder and external atmosphere and close communication between the air supply, the air feed cylinder and the hammer; when in its second position to close communication between the air feed cylinder and external atmosphere and between the air supply and hammer and to open communication between the air supply and air feed cylinder; and when in its third position to open communication between the air supply, the air feed cylinder and the hammer.

3. In an air feed hammer drill, a head block, an air supply, an air feed cylinder, its piston, a manually operated valve in the head block for controlling communication between the air supply, the air feed cylinder and the hammer and means for automatically locking the valve in its different positions against unintentional displacement.

4. In an air feed hammer drill, a head block, an air supply, an air feed cylinder, its

5 piston, a manually operated valve in the head block for controlling communication between the air supply, the air feed cylinder and the hammer, and means for automatically locking the valve in its different positions against unintentional displacement comprising a locking plate on the valve having sockets therein and a spring actuated pin mounted in the head block arranged to 10 enter the socket which is brought into alignment therewith.

5. In an air feed hammer drill, a hammer cylinder, an air feed cylinder, a head block interposed between the two cylinders, an air 15 supply and a manually operated valve seated in the head block having a chamber therein communicating with the air supply and having ports therein for controlling communication between the air supply, the air feed 20 cylinder and the hammer, the pressure of the air supply serving to hold the valve snugly in its seat.

6. The combination with a pressure fluid tool, of pressure fluid feeding means therefor, a single controlling device for said tool and feeding means, said device being adapted to be moved to one or more positions intermediate its extreme positions, and positioning means for said controlling device 30 operative in any one of the said positions.

7. The combination with a pressure fluid tool, of pressure fluid feeding means therefor, and a controlling throttle for said tool and said feeding means adapted to admit the 35 pressure fluid, first to the feeding means and then to the tool, without interrupting the supply of pressure fluid to the feeding means.

8. The combination with a pressure fluid 40 tool, of pressure fluid feeding means therefor, and a controlling device adapted to admit pressure fluid to the feeding means and there maintain the supply while varying the pressure fluid admitted to the tool.

45 9. The combination with a pressure fluid tool, of pressure fluid feeding means therefor, a controlling device having a plurality of positions, wherein the said device may admit pressure fluid to said tool in varying 50 amounts, and a pressure fluid supply passage leading to said feeding means and controlled by said controlling device, said device acting to supply pressure fluid through said passage to said feeding device in each 55 of several positions wherein pressure fluid is admitted to said tool.

10. The combination with a pressure fluid tool, of pressure fluid feeding means therefor aligned therewith, and throttling means 60 both for the tool and the feeding means and located in a space between the same.

11. The combination with a pressure fluid tool, of pressure fluid feeding means therefor, and a controlling device having a plurality of positions, said device in one posi-

tion shutting off pressure fluid from said tool and feeding means, in another position admitting pressure fluid to said feeding means only, and in a third position admitting pressure fluid to said feeding means 70 and said tool, said device passing from said second to said third position acting to maintain admission of pressure fluid to the feeding means.

12. In a structure of the character set 75 forth, the combination with a motor, of feeding means connected thereto and comprising a cylinder and a piston operating in the cylinder, and means for supplying motive fluid to the motor independently of the cylinder 80 and piston, said supplying means also supplying motive fluid to the cylinder and including common means for controlling the supply of motive fluid to both the motor and feeding means and to one separately from 85 the other.

13. In a structure of the character set 90 forth, the combination with a motor, of feeding means connected thereto and comprising a cylinder and a piston operating in the cylinder, and means for supplying motive fluid to the cylinder and also to the motor, independently of said cylinder said supplying means including common means for controlling the supply of motive fluid to both the 95 motor and feeding means and to one separately from the other.

14. In a structure of the character set 100 forth, the combination with a motor, of feeding means connected thereto and comprising a cylinder and a piston operating in the cylinder, and means for supplying motive fluid to the cylinder and also to the motor independently of said cylinder, said supplying means including a single valve 105 for controlling the supply of motive fluid to both the motor and feeding means and to one separately from the other.

15. In a structure of the character set 110 forth, the combination with a motor, of feeding means therefor including a cylinder member and a piston member operating in the cylinder member, a connection between one of the members and the motor, and a valve mechanism located in the connection 115 for separately controlling the supply of motive fluid to the feeding means and to the feeding means and motor.

16. In a structure of the character set 120 forth, the combination with a motor, of feeding means therefor including a cylinder member and a piston member operating in the cylinder member, a connection between one of the members and the motor interposed between the same, said connection 125 having ports respectively leading to the feeding means and to the motor, and a motive fluid controlling valve having supply ports that are movable into and out of coaction with the first mentioned ports. 130

17. In a structure of the character set forth, the combination with a motor, of feeding means therefor including a cylinder and a piston operating in the cylinder, a connection between the cylinder and the motor interposed between the two, said connection having a valve seat and ports leading from the seat and communicating respectively with the motor and the cylinder, a rotary valve having ports that are movable into and out of coaction with the first mentioned ports, and means for supplying motive fluid to the valve.
18. In a structure of the character set forth, the combination with a motor, of fluid operated feeding means therefor, a valve casing interposed between the motor and feeding means, said valve casing having a valve seat located therein transversely of said feeding means and motor, and a valve for controlling the supply of motive fluid to the motor and feeding means, said valve operating in the valve seat.
19. In a structure of the character set forth, the combination with a motor, of fluid operated feeding means therefor, a valve casing interposed between the motor and feeding means, said valve casing having a valve seat located therein transversely of said feeding means and motor, and ports leading from the valve seat to the motor and feeding means, and a rotary valve for controlling the supply of motive fluid to the motor and feeding means, said valve operating in the valve seat.
20. In a structure of the character set forth, the combination with a motor, of fluid operated feeding means therefor, a valve casing between the motor and feeding means having a valve seat located therein, and ports leading from the seat to the motor and feeding means, a valve operating in the seat, and means for supplying motive fluid to the valve.
21. In a structure of the character set forth, the combination with a motor, of fluid operated feeding means therefor, a connection between the motor and feeding means having a valve seat located therein, and ports leading from the seat to the motor and feeding means, a valve operating in the seat, and having supply ports that move into and out of register with the first mentioned port, and means for supplying motive fluid to the ports in the valve.
22. In a structure of the character set forth, comprising a body having a motor at one end and motive fluid operated feeding means at the other end, a valve located transversely in said body and interposed between the motor and feeding means for

controlling the supply of motive fluid to both, and means for delivering motive fluid into said valve.

23. A structure of the character set forth, 65 comprising a body having a motor at one end and motive fluid operated feeding means at the other end, a motive fluid controlling valve located in the body and having an actuating handle projecting from 70 one side of the body, and means connected to the opposite side of the body for conducting motive fluid to the valve.

24. In a structure of the character set forth, a motor, motive fluid operated feed- 75 ing means therefor, a body interposed between the motor and feeding means, a controlling valve having an internal chamber, and ports leading therefrom, said valve projecting from one side of the body, and means connected to the opposite side of the body for conducting motive fluid to the internal chamber of the valve.

25. In a structure of the character set forth, the combination with a motor, of motive fluid operated feeding means therefor, 85 a body interposed between the motor and feeding means, said body having a valve seat, and ports leading therefrom to the motor and to the feeding means, a rotary 90 controlling valve arranged in the seat and having an internal chamber and ports leading therefrom, said ports being movable into and out of communication with the first mentioned ports, said valve projecting 95 from one side of the body, and a motive fluid feed conduit having a coupling connected to the opposite side of the body and delivering to the internal chamber of the valve.

26. In a structure of the character set forth, the combination with a motor, of feeding means therefor including a cylinder member and a piston member operating in the cylinder member, a connection between 100 one of the members and the motor located between the same, and valve mechanism located in the connection and interposed between the motor and member for controlling the supply and exhaust of motive fluid to 110 and from the feeding means and for controlling the supply of motive fluid to the motor.

In testimony, that I claim the foregoing as my invention I have signed my name in 115 presence of two witnesses, this 28th day of September, 1907.

ALBERT H. TAYLOR.
